UNITED STATES PATENT OFFICE.

BENJAMIN SKIDMORE, JR., OF CHICAGO, ILLINOIS.

HYDROTURBINE VACUUM-PUMP.

1,312,707.

Specification of Letters Patent. Patented Aug. 12, 1919.

Application filed March 9, 1918. Serial No. 221,361.

To all whom it may concern:

Be it known that I, BENJAMIN SKIDMORE, Jr., a citizen of the United States, residing at Chicago, in the county of Cook and State 5 of Illinois, have invented certain new and useful Improvements in Hydroturbine Vacuum-Pumps, of which the following is a specification.

This invention relates to improvements in 10 hydroturbine vacuum pumps and one of the objects of the invention is to provide an improved submerged pump of this character for creating a suction or vacuum. A further object is to provide an improved device of 15 this character which will be simple, durable, cheap and compact in construction and effective and efficient in operation.

To the attainment of these ends and the accomplishment of other new and useful objects as will appear, the invention consists in 20 the features of novelty in substantially the construction, combination and arrangement of the several parts hereinafter more fully described and claimed and shown in the accompanying drawing, illustrating this invention and in which,

Figure 1 is a vertical sectional view of an 25 improved apparatus of this character constructed in accordance with the principles of this invention.

Fig. 2 is a horizontal sectional view taken on line 2—2, Fig. 1.

Fig. 3 is an enlarged detail sectional view 30 of one of the nozzles.

Referring more particularly to the drawing, the numeral 10 designates generally a 35 tank or receptacle preferably provided with a top 11, having an outlet opening 12 from which a pipe 13 leads. This tank or receptacle may be supported in any desired or suitable manner and may be of any desired 40 size and construction and is adapted to hold a quantity of liquid 14.

Arranged within the receptacle is a 45 rotary element designated generally by the reference numeral 15 and in which element there is provided a chamber 16, having an inlet opening 17 and a plurality of outlet 50 openings 18, the latter being arranged preferably to extend through the periphery of the element. These outlet openings may be of any desired size, and connected with the element so as to extend over each of the 55 openings 18 is a hood 19, of any desired length having both of its ends 20, 21 open, and the outlet opening 18 has communica-

tion with the hood preferably intermediate the ends of the latter. The end 20 of the hood is shaped to form an injector 22 which extends into the hood and terminates preferably adjacent the opening 18, so that when the element 15 is rotated in the direction indicated by the arrow in Fig. 2, the liquid in the receptacle 10 will be injected into the hood by passing first through the nozzle portion 22 through the reduced outlet 23 and then out of the opposite end of the hood. The liquid will flow into the nozzle 22, and will be discharged through the outlet end 23 in the form of a spray and will substantially 60 fill the hood, thereby operating as an aspirator which will entrain the fluid through the openings 18 of the chamber 16. The fluid flowing through the nozzle 22 and the fluid flowing through the openings 18 will 65 commingle and be discharged therefrom through the outlet end 21 of the hood.

The extremity of the injector 22 is reduced as at 23 to form a narrow edge, preferably terminating adjacent the opening 18, so that 70 the suction or the entrainment of the fluid from the chamber by the liquid will not be interfered with. Connected with the inlet opening 17 of the chamber 16 is a suitable 75 pipe 24, in which it is desired to create a suction.

Within the chamber 16 are a series of wings or partitions 25 one of which extends from the periphery of the chamber 16 adjacent each of the openings 18, and these 80 wings extend toward the center of the chamber and terminate short of each other and act as impellers for assisting in impelling or driving the fluid from the chamber 16 to the outlet 18 as the element is rotated. These 85 impellers 25 may be of any desired shape and of any desired length.

The element 15 is rotated by means of a shaft 26 connected thereto and which shaft passes through a suitable bushing 27 and is 90 connected with a suitable motor 28 by means of a suitable flexible connection 29.

In operation, it will be apparent that when 95 the element 15 is rotated in the direction of the arrow, the liquid in the tank or receptacle 10, being held against a rotary motion by means of suitable baffles 30, will flow through the hoods 19 with such force, that a suction will be created in the pipe 24 through the chamber 16 and out of the outlet 105 18, the degree of suction being of course controlled by the speed of rotation of the ele-

ment 15. The fluid which is drawn into the chamber 16 will be thus discharged into the receptacle 10 and into the body of the liquid 14 therein, so that the fluid which is not condensed will rise through the liquid 14 into the upper part of the receptacle 10 and will then pass through the outlet 12 and through the pipe 13. Obviously, if desired, a suitable valve may be provided in the pipe 13 to retain the fluid within the receptacle 10 to be compressed therein.

A suitable clean-out valve 31 may also be provided in the bottom of the receptacle 10.

With this improved construction, it will be manifest that a very powerful suction pump will be produced and which suction will be manifested in a suction pipe with which the element has connection.

The interior of the hood 19 may, if desired, be slightly reduced in diameter intermediate its ends and beyond the injector 22, so as to increase the efficiency of the device.

What is claimed as new is:

1. An apparatus of the character described embodying a submerged rotary element circular in cross section having a fluid chamber therein, said chamber being provided with an inlet and having an outlet through the periphery of the element, a hood connected with the periphery of element and extending across said outlet, said hood embodying a conical nozzle adjacent one end of the hood, the larger portion of the nozzle being disposed adjacent the leading end of the hood and the smaller portion terminating within the hood and at a considerable distance from the trailing end of the hood, whereby when the element is rotated the submerging liquid forced through the nozzle will be discharged into the hood in the form of a spray and substantially fill said hood to create a suction through the said outlet of the said element, and means for rotating the said element.

2. An apparatus of the character described embodying a submerged rotary element circular in cross section and having a fluid chamber therein provided with an inlet and an outlet, said outlet opening through the periphery of the element, a hood connected with the periphery of the element extending across and about the periphery of said outlet, said hood embodying a conical nozzle adjacent one end of the hood, the larger portion of the nozzle being disposed adjacent the leading end of the hood and the smaller portion terminating within the hood and at a considerable distance from the trailing end of the hood, whereby when the element is rotated the

submerging liquid forced through the nozzle will be discharged into the hood in the form of a spray and substantially fill said hood to create a suction through the said outlet of the said element, means for rotating the said element, and one or more stationary brakes adjacent the path of movement of the said element for maintaining the submerging liquid against rotation.

3. An apparatus of the character described embodying a submerged rotary element having a fluid chamber therein provided with an inlet and an outlet, a hood connected with the element and extending across said outlet, said hood embodying a conical nozzle adjacent one end of the hood, the larger portion of the nozzle being disposed adjacent the leading end of the hood and the smaller portion terminating within the hood and at a considerable distance from the trailing end of the hood, whereby when the element is rotated the submerging liquid forced through the nozzle will be discharged into the hood in the form of a spray and substantially fill said hood to create a suction through the said outlet of the said element, means for rotating the said element, and an impeller wing or blade within the chamber, said impeller extending from the point of communication of the chamber with the said hood toward and terminating in proximity to the center of the chamber.

4. An apparatus of the character described embodying a submerged rotary element substantially circular in cross section and having a fluid chamber therein, said chamber having an inlet and being provided with a plurality of outlets, said outlets opening through the periphery of the element, hoods individual to the outlets and connected directly with the periphery of the element, each hood extending about the said periphery, said hoods each embodying a conical nozzle with the larger portion adjacent the leading end of the hood, and the smaller portion of the nozzle terminating within the hood and at a considerable distance from the trailing end of the hood whereby when the element is rotated the submerging liquid forced through the nozzle will be discharged into the hood in the form of a spray and substantially fill the hood to create a suction through the respective outlets of the said element, and means for rotating the element.

In testimony whereof I have signed my name to this specification, on this 6th day of March, A. D. 1918.

BENJAMIN SKIDMORE, JR.
